Primary Examiner — Rashida C. Walshon(74) *Attorney, Agent, or Firm* — Rosenberg, Klein & Lee(57) **CLAIM**

The ornamental design for sandals, as shown and described.

DESCRIPTION

FIG. 1 is a perspective view of a sandal showing my new design.

FIG. 2 is a front view thereof.

FIG. 3 is a back view thereof.

FIG. 4 is a plan view thereof.

FIG. 5 is a rear view thereof.

FIG. 6 is a left side view thereof; and,

FIG. 7 is a right side view thereof.

Shown is a sandal for the left foot. The sandal for the right foot has a symmetrical figure.
